CLAIM

The ornamental design for an air fryer drawer as shown and described.

DESCRIPTION

FIG. 1 is a perspective view of an air fryer drawer showing the new design;

FIG. 2 is a left side view thereof;

FIG. 3 is a right side view thereof;

FIG. 4 is a front view thereof;

FIG. 5 is a rear view thereof;

FIG. 6 is a top view thereof; and,

FIG. 7 is a bottom view thereof.

The evenly dashed broken lines depict portions of the air fryer drawer that form no part of the claimed design. The dot dash lines depict the boundaries of the claim and form no part of the claimed design.

1 Claim, 5 Drawing Sheets
